UNITED STATES PATENT OFFICE.

FRANK LEWIS PRIEST, OF DALLAS, TEXAS.

PESSARY.

SPECIFICATION forming part of Letters Patent No. 748,650, dated January 5, 1904.

Application filed April 7, 1903. Serial No. 151,480. (No model.)

To all whom it may concern:

Be it known that I, FRANK LEWIS PRIEST, a citizen of the United States, and a resident of Dallas, in the county of Dallas and State of Texas, have invented a new and Improved Pessary, of which the following is a full, clear, and exact description.

This invention relates to mechanical means for supporting the womb to prevent painful flexions and displacement, relieve painful menstruation, and provide for drainage in cases of ulceration, and has for its objects to provide an appliance of the character indicated that is of novel simple construction, is very light, is compact and devoid of abrupt projections, thus avoiding injurious abrasion of tissue, that may be conveniently self-applied or removed, that may be worn without discomfort for any desired length of time, and that will afford safe, convenient, and reliable means for the application of medicaments to diseased parts, or a suitable tampon to check dangerous hemorrhage.

The invention consists in the novel construction of the improved pessary and of means for its application, as is hereinafter described, and defined in the appended claims.

Reference is to be had to the accompanying drawings, forming a part of this specification, in which similar characters of reference indicate corresponding parts in all the figures.

Figure 1 is a perspective view of the pessary and of the handle-support employed for its proper disposition when applied. Fig. 2 is an enlarged longitudinal sectional view of the improvement and of a portion of the handle-support therefor, showing the detachable connection between said parts; and Fig. 3 is a plan view of the pessary.

The improved appliance is preferably constructed of plate metal cut and struck into form or otherwise shaped from a planchet of such material.

As shown, the improvement comprises a circular abutment-ring 4 of proper diameter and thickness, from which a plurality of similar slim arms 5 project in the same direction and are preferably spaced apart an equal distance. There are four arms 5 shown, but if desired more may be employed, and near the ends which are farthest from the ring 4

said portions of the arms are convexly curved, as at *a*, so as to merge their extremities in a central eyelet-ring 6 of small diameter, the orifice *b* through which is in the same longitudinal plane with the center of the ring 4. Near the abutment-ring 4 the arms 5 are similarly incurved, as at *c*, forming a concave surface on the exterior of each arm at and near said ring, these concavities on the exteriors of the arms merging into the convex portions *a* and producing a skeleton bulb at and near the normal posterior end of the device. It will, furthermore, be seen that the concavities *c* in the set of spaced arms 5 reduce the diameter of the skeleton frame and produce a neck between the abutment-ring 4 and the bulbous formation hereinbefore described.

To facilitate the proper insertion of the pessary, a preferably tubular straight stem 7 is provided of proper length, having a ring-like handle 7^a at one end for the engagement of a finger of the wearer of the device, which enables the secure holding and manipulation of the stem. At the opposite end of the stem 7 a small bead *d* is formed by peripherally grooving the hollow body of the stem close to the extremity and rounding the edges of the slight collar thus produced. The edges of the eyelet-ring 6 at each end of its transverse perforation are rounded, and the diameters of said perforation and of the bead *d* are so proportioned that the latter may be passed into the eyelet-ring and effect a detachable connection therewith, which will retain the skeleton frame of the pessary in position on the end of the stem 7 in a manner which will permit the proper insertion of the appliance in a convenient manner and its removal when desired.

In use of the pessary as a mechanical means for obviating spasmodic flexions or contractions of the os in the diaphragm intervening the womb and uterus, and thus correcting obstruction to the menses and incidental pain, the skeleton frame of the appliance is introduced by manipulation of the stem 7, whereon the device is mounted, and an insertion of the bulbous end of the frame 4 through the os into the womb until the ring 4 abuts upon the diaphragm, the slight dilat-

tion of tissue produced by the neck of the skeleton frame serving to retain the appliance in position.

Obviously from the relative position of the pessary a drainage-passage is afforded, injury to engaged parts is prevented, and no discomfort is experienced when the wearer is sitting or walking.

In cases where disease requires the positive application of medicament either in powdered or liquid form antiseptically-prepared fiber, such as sterilized cotton, is introduced within the skeleton frame of the pessary, and before its application the cotton filling is either coated or saturated with the medicinal powder or liquid, which may then be readily conveyed into positive contact with the diseased membranous tissue and may remain so applied until a renewal of the medicament is desired.

The appliance may be used with great advantage when filled with fibrous material to restrain hemorrhage, it then serving as a plug or tampon which may hold an astringent to arrest the flow of blood in dangerous cases.

The device may be formed of gold, silver, or other metal that does not corrode, or the frame may be plated with metal that is not liable to oxidate. The edges of the members of the skeleton frame are rounded, so that no injury can result from its use.

It is to be understood that when the pessary is applied by the employment of the stem 7 after the device is placed in position, as before explained, the stem can and should be disconnected and removed, its reengagement with the eyelet-ring 6 for removal of the pessary when this is desired being readily effected in an obvious manner. It will be apparent, however, that the pessary may be removed by the fingers, if desired.

Having thus described my invention, I claim as new and desire to secure by Letters Patent—

1. A pessary comprising a skeleton frame 45 formed of a plurality of spaced arms extended from the inner side of a flat abutment-ring, said arms converging to a central eyelet-ring and curving outward near said eyelet-ring to provide a skeleton bulb for the frame. 50

2. A pessary comprising an abutment-ring, a plurality of slim, spaced arms extended at the same side of the ring, the extended end portions of the arms being curved toward a central eyelet-ring, into which they merge 55 and provide a bulb, the arms between the rings having incurved portions that produce a neck of less diameter than the bulb and abutment-ring.

3. A pessary, comprising an elongated skeleton frame, consisting of an abutment-ring forming one end of the frame with a plurality of spaced arms extending from the ring, and all curved inwardly and upwardly toward a common center to form a contracted neck portion for the pessary, said arms then continuing in the same longitudinal direction and curving slightly outwardly from each other to form a bulb portion, the arms then curving into arches and all meeting at a common 70 center to form the other end of the pessary, said ring being of greater diameter than the diameter of said bulb portion, whereby said ring forms a stop for the device.

In testimony whereof I have signed my 75 name to this specification in the presence of two subscribing witnesses.

FRANK LEWIS PRIEST.
